United States Patent Office.

AZRO M. BOWLES AND HIRAM PRESTON, OF ORFORDVILLE, WISCONSIN.

Letters Patent No. 66,451, dated July 9, 1867.

IMPROVEMENT IN WATER-ELEVATORS.

The Schedule referred to in these Letters Patent and making part of the same.

TO ALL WHOM IT MAY CONCERN:

Be it known that we, AZRO M. BOWLES and HIRAM PRESTON, of Orfordville, Rock county, in the State of Wisconsin, having invented new and useful improvements in Apparatus for Raising Water, do hereby declare the following to be a full and exact description of the same, reference being had to the drawings that accompany and form a part of this specification, in which—

Figure I is a front elevation.

Figure II, sectional view cut through the centre.

Figure III, bucket used in open wells, showing the interior parts.

Letter A, box or housing; B, shaft; C, pulley; D, crank; E, brake; F, lever to operate the brake E; a, button to hold the lever F while the bucket is descending; g, pawl; h, rod or strap connecting E and F; i, well-rope or chain; j, valve or bottom of bucket; k, rocking-shaft; l and m, levers to operate the shaft k with; O, delivery spout; P, bucket for drilled wells.

The object of our invention is to provide an easy method of raising water from curbed or drilled wells, by a windlass, and so to arrange the various parts as to have the whole compact in form, simple and durable in structure, and easy of operation, by bringing the pawl g and brake E under the operation of a single lever. An examination of the drawings will give a correct understanding of the general structure.

Fig. I will show the manner of arranging the shaft B, brake E, lever F, and button a. When the shaft B is being revolved by the crank D, and the lever F at rest, the pawl g will fall into the ratchet on the shaft and hold it. When the bucket has been emptied, and it is desired to allow it to drop into the water again, a depression of the end of the lever F will disengage the pawl, and the bucket will begin to descend, and should it tend to do so too rapidly, a further depression of the lever F will bring the brake E up against the truck on the end of the shaft, and check its revolutions. The button a is so attached that on depressing the lever F, it will swing down on its pivot and assume the position of the red lines in Fig. I. This is to prevent any accidental movement of the lever F upwards, while the bucket is descending, so the pawl g cannot fall into the ratchet until the button a is lifted again. Perfect control is thus had of the descent of the bucket. Without this there is serious objection to the use of the windlass. The rocking-shaft in the bucket, together with the two levers l and m, provides a sure and easy method of operating the valve to empty the bucket.

The peculiarity of the arrangement in the interior of the bucket is this: We place a horizontal shaft, k, some distance above the bottom of the bucket, the two ends resting either in the two opposite walls of the bucket, or on short posts S S, as in Fig. III. These posts being placed far apart so that the valve may extend back under the shaft k, and cover, if need be, nearly, and indeed in buckets of small diameter the whole bottom, securing a rapid filling and emptying not attainable by small valves.

For wells open, in which the bucket may have more or less vibration in descending or ascending, the curb and spout would be arranged to bucket shown in Fig. III. The bucket, for drilled wells, would be made so as to nearly fill the bore of the well.

What we claim, and desire to secure by Letters Patent, is—

The combination and arrangement of the pawl g, the ratchet on the shaft B, the brake E, and lever F, and button a, to operate as described and set forth.

AZRO M. BOWLES,
HIRAM PRESTON.
